UNITED STATES PATENT OFFICE

LE ROY W. FAIRCHILD, OF NEW YORK, N. Y.

DESIGN FOR PENCIL-CASES.

Specification forming part of Design No. 11,419, dated September 16, 1879; application filed August 7, 1879.
[Term of patent 7 years.]

To all whom it may concern:

Be it known that I, LE ROY W. FAIRCHILD, of the city, county, and State of New York, have produced a new and original Design for Ornamental Pencil-Cases, or cases for like small implements, to be worn as amulets upon watch-chains or otherwise, of which the following is a full, clear, and exact description, reference being had to the accompanying engraved illustration, making a part of this specification.

A represents a clear front view of my design in its entirety. a is the outer tube or shell of the pencil-case proper. b is the stem-ring. c is a head ornament in the form of a crown. d e are two animal figures at opposite sides of the shell a, standing rampant upon a bracket or pedestal, g. f is an anchor in bas-relief formed upon the case and resting upon a sphere, also in bas-relief.

What I claim as my invention is—

A design for an ornamental pencil-case, consisting of the shell or tube a, the ring b, the crown c, the two animal figures d and e, the anchor f, and the bracket g, substantially in the manner shown and described.

LE ROY W. FAIRCHILD.
